Attorney

UNITED STATES PATENT OFFICE

2,279,189

REMINDER APPLIANCE

Charles H. Uhlig, Cleveland, Ohio

Application August 11, 1941, Serial No. 406,358

5 Claims. (Cl. 116—130)

The purpose of this invention has been to devise a novel type of reminder appliance or device, suitably for use in any place where supplies are required to be procured from time to time, but susceptible of employment so far as general principles of operation are concerned, as a means for reminding or calling up matters of any sort that in the future have to be taken care of.

In its preferred embodiment only, my invention may take the form of a reminder appliance useful in the home, for instance, to enable a housewife to quickly provide an indication upon the appliance, by which to check and remind her to procure certain supplies for the home, as for instance, provisions for the table, drugs, or anything of this sort.

It has been proposed heretofore to avail of reminder devices, as for instance, the type utilizing a baseboard having indicia of different kinds of supplies thereon, with openings opposite the indicia into which pegs may be inserted in the said openings to indicate particular supplies that may be required to be secured. My invention is especially useful for a like purpose, but a particular object in view has been to provide an appliance of a more simple and cheap nature or construction than the type above mentioned for the purposes in view.

A special object of my invention has been to design an appliance of the class described made entirely of paper.

Another object of the invention has been to utilize an appliance of the class described made of paper that may be readily printed by an ordinary printing shop with customary paper printing facilities, and which may be utilized as a calendar or provide an ornamental or interesting picture, either each alone, or in conjunction with one another.

In the carrying out of my invention, I utilize an appliance made from a sheet of paper which is cut in a peculiar way to provide indicator tabs printed with indications of supplies or things to be the subject matter of future attention. The said sheet is formed with means for engaging the tabs in such a way that normally they do not indicate, but are permitted to be quickly adjusted to a position to afford the desired indication.

An embodiment of my invention, in just one preferred form in which it may be used as a regular annular calendar, is illustrated in the drawing, in which—

Figure 1 is a plan view of my reminder appliance incorporating a calendar as a part thereof, certain of the tabs in the view being adjusted as

when they are performing their indicating function, and other of the tabs being positioned as when they are not so indicating.

Figure 2 is a plan view of the blank of material from which my reminder appliance is made, the manner in which the tabs are cut being fully illustrated along with the special reminder indicia carried by each tab.

Figure 3 is a cross sectional view taken about 10 on the line 3—3 of Figure 1 showing one of the reminder tabs in position to perform its reminder function, and the other not in such position.

Describing my invention specifically, and referring to the drawing, I note that my reminder appliance comprises especially a body 1 consisting of a sheet of paper or cardboard material, or any equivalent material, because cloth might readily be employed, if desired, dependent upon the particular use of the appliance, the length of its use, and the conditions to which it will be subjected in use as to wear and tear.

The body or sheet 1 is made in its original blank form as per its construction, seen best in Figure 2, wherein it will be noted that side flaps or extensions 2 extend along the body nearly the entire length thereof, but terminating short of the upper and lower ends preferably, though not necessarily. The flaps or extensions 2 are provided with adhesive substance 3 thereon, near the extremities, and in the completion of the appliance, they are folded over on to the main part of the body 1, as seen in Figure 1, and the adhesive portions 3 are adhesively connected with said main portions of the body so as to hold the flaps 2 flat upon the body.

The side portions of the body or sheet 1 more adjacent to the flaps or extension portions 2 are prepared in the formation of the appliance by providing a series of horizontal slits 4, at relatively close intervals, one below the other, from a point near the upper portion of the body 1 to the point near the lower portion of the body.

The formation of these slits 4 provides a series of adjacent or contiguous tabs 5, each of which tabs constitutes a reminder tab being supplied with printed indicia thereon, indicating an article to be supplied, designated 6, or constituting an indication or memorandum of something to be performed in the future.

The tabs 5, as constructed by the slits 4, are wholly separated at their outer ends from the sheet or body 1, whereas, at their inner ends, they are integral portions of the sheet, and thus at these inner ends are flexibly or hingedly connected with the sheet body.

The foregoing arrangement and construction permits the outer ends of the tab 5 to be lifted, and when the appliance is in complete form, the flaps or extensions 2 overlie the outer free ends of the tabs, but permit said ends to be disengaged or lifted up so as to be adjusted in a position extending over the flap 2, which is the indicating position of the tabs in the preferred use of the invention.

In order that the user of my appliance may quickly visually observe the condition of adjustment of the tabs 5, I contemplate coloring the free ends of the tabs with color blocks in black, or any other color, as designated at 7.

According to the illustration of Figure 1, a calendar A may be applied to the front lower portion of the body or sheet 1, and the frame, designated B, may be used as a panel to enclose a picture pasted, or otherwise printed upon the body 1, if ornamental of the appliance is desired, as well as special utility in regard to the employment of the calendar. Of course, either the picture or calendar may be dispensed with within the purview of my invention, and other matter might be substituted for these items so far as employment of the invention is concerned.

The operation of my appliance is understandable from the foregoing, but may be briefly noted to be as follows:

The person using the appliance whenever desiring to be reminded of the procurement of a supply, or any other item, for which the appliance is to be employed, will raise a tab or tabs 5, which carry the reminder indicia 6 appropriate to be used. By raising the tab which may be done quickly by inserting the finger-nail underneath the upper edge of the tab 5 through one of the slits 4, the outer end of the tab with its indicia 7 may be adjusted so as to overlie the flap 2 and this will bring sharply to the attention of the user the particular matter of which the person desires to be reminded.

When the reminder function of the tab 5 so adjusted has been performed, the user simply reinserts the outer end of the tab beneath the flap 2, which freely overlies the same, and the reminder function of the tab is thus ended.

Having thus described my invention, what I claim as new and desire to secure by Letters Patent of the United States, is:

1. A reminder appliance of the class described, comprising a body in the form of a sheet of material, said body being provided with slits at intervals therein dividing a portion of the body into tabs movable to reminder positions relatively to the body, said tabs having reminder indicia thereon, and the body being formed with an integral extension folded over upon the body to engagingly overlie a portion of the reminder

tabs, the reminder tabs being adapted to be adjusted, however, to be disposed with such portion above the folded-over extension of the body when the tabs are disposed in a reminder position.

2. A reminder appliance comprising a body in the form of a sheet of material, said body being provided with slits at intervals thereon dividing a portion of the body into tabs adjustable to reminder positions relatively to the body, said tabs having reminder indicia thereon, the body being provided with an extension adapted to be folded over and engagingly overlie a portion of the tabs, one end of each tab being free from the sheet to enable it to be adjusted by movement toward and from the sheet body and the other end of the tab being integral with the body or sheet by reason of the formation of the slits, the free ends of the tabs being thus engageable or disengagable with the extension.

3. As a new article of manufacture, a reminder appliance comprising a sheet of material having a flap at its side edge folded over onto the body thereof, and said sheet cut to form integral reminder tabs having reminder indicia thereon, carried by the sheet of material, and having portions engageable beneath and adjustable to positions above the said flap.

4. As a new article of manufacture, a reminder appliance comprising a single sheet of material provided with a series of contiguous tabs formed by separating slits in the material, the said tabs at one end being integral with the sheet of material and at the other end being separable therefrom, and said sheet of material being provided with integral parts adapted to overlie the separable ends of the tabs and beneath and above which said ends may be adjusted.

5. As a new article of manufacture, a reminder appliance comprising a single sheet of material provided at an edge thereof with a series of slits forming the slitted portion of said sheet into a series of contiguous tabs, reminder indicia carried by said tabs, corresponding ends of the tabs being integral with the sheet and the opposite ends being freely movable so that each tab may be moved to an adjusted reminder position independently of the other tab, the sheet being formed adjacent the edge portion thereof provided with said slits, and tabs, with an extension that is folded over onto the top of the sheet and adapted to overlie the free or movable ends of the tabs, said extension having adhesive material applied thereto at its opposite ends so as to adhesively connect it to the body of the sheet at points beyond the area of the sheet at which the slitted tabs are formed.

CHARLES H. UHLIR.
